UNITED STATES PATENT OFFICE.

HENRY B. HELM, OF NEW YORK, N. Y.

NOZZLE.

No. 922,895.

Specification of Letters Patent.

Patented May 25, 1909.

Application filed January 7, 1909. Serial No. 471,087.

To all whom it may concern:

Be it known that I, HENRY B. HELM, a citizen of the United States, and a resident of the borough of Manhattan, city and State of New York, have invented certain new and useful Improvements in Nozzles, of which the following is a full and complete disclosure.

The object of my invention is to produce a nozzle, or nozzle tip, particularly intended for use with fire hose for extinguishing fires, and so arranged that not only may different sizes of streams be thrown from a single nozzle, but also a spray may be produced to cover large areas of the combustible matter in the immediate vicinity.

A further object of my invention is to provide a nozzle which will throw a backwardly direct series of jets or spray, so that said nozzle may be used as a "distributer" for throwing water over the entire interior surface of an inclosed space, or a room, when said nozzle is inserted through an opening in one wall thereof.

Other advantages of my improved nozzle will be apparent from the following description, and will be particularly pointed out in the accompanying claims:

For a detailed description of one form of my invention, which I at present deem preferable, reference may be had to the following specification and to the accompanying drawing forming a part thereof, in which—

Figure 1 is a longitudinal sectional view of my improved nozzle; Fig. 2 is a side elevation thereof; Fig. 3 is a transverse sectional view taken substantially on the line A—A of Fig. 1; Fig. 4 is a longitudinal sectional view of several different forms of tips shown assembled, and which may be used to produce different sizes and character of streams from the main outlet of the nozzle. Fig. 5 is a plan view of the perforated tip which may also be used to throw a single small stream, when arranged as shown in Fig. 4.

Referring to the drawings, 1 indicates a reducer section or bushing which is screw-threaded so as to fit within my improved tip, and which may be varied in size at its outer end so as to accommodate different sizes and makes of nozzles now on the market. This reducer or coupling 1 screws into the main casing 2, which is preferably composed of two screw-threaded parts 3 and 4 united by an interiorly screw-threaded union or ring 5. Within the ring 5, and so placed as to be held

in position by the adjacent ends of the sections 3 and 4 of the casing, is a spider 6, preferably made of phosphor bronze, or some similar tough infrangible material.

The flange 7, uniting the inner ends of the spider arms 6, is rigidly fastened to a screw-threaded tube 8 which forms the outlet proper for the nozzle or tip when the largest size stream is used. The screw-threaded tube 8 carries a conical or cup-shaped part 9, having a conical surface 10, which coöperates with the end 11 of the casing 2 to form an annular opening through which water may be forced in the form of a spray. The conical section 9 is provided with two arms secured adjacent its outer ends, and diametrically opposite each other as indicated at 12. These arms extend parallel with the axis of the tip or nozzle, and enter ears 13 carried by the ring 14 rotatably held in position on the casing 2 by means of the coupling ring 5.

The lower end of the section of the casing 2 is provided with screw-threads which connect it with a milled ring 15, so that when said ring is turned, the same will be moved longitudinally in relation to the axis of the tip or nozzle. Section 4 of the tip is provided with a series of inclined holes or openings 16 which extend toward and away from the outer end of the tip, and these openings 16 are adapted to be covered by the ring 15 when at the upper limit of its motion on section 4 of the casing. A washer or packing ring 17 may be inserted between the end of the coupling ring 5 and the ring 15 to further aid in securing a water-tight joint between said parts, and prevent water issuing through the opening 16 when the same is not in use. The bushing or reducer 1 carries a pin 18 which limits the motion of the ring 15 and prevents it from becoming disengaged from the section 4.

The numeral 19 indicates a reducing tip which has a central tubular interiorly tapered portion 20 adapted to fit within the tube 8, and its upper end is provided with a tubular flange 21 which is interiorly threaded and adapted to engage the screw-threads on the exterior of the tube 8. The outer end 22 of this tip is also screw-threaded in order that a still further reduction in the size of the stream may be secured by the use of the parts shown in section in Fig. 4. These parts consist of an interiorly screw-threaded cup-shaped portion 23 having an interiorly screw-threaded nipple 24. The latter re-

ceives the screw-threaded tubular projection 25 of the perforated tip 26. The opening through the tip 26 is preferably 3/16ths of an inch in diameter, to provide a very small 5 stream, while the opening in the tapering tube 20 is $\frac{3}{4}$ of an inch in diameter, in order to provide a stream of medium volume, the internal diameter of the tube 8 being preferably $1\frac{3}{4}$ inches in diameter, which is the 10 standard size used in fire nozzles. It will be noticed that the tip 26 is also cup-shaped and provided with a number of openings 27, the interior of the cup-shaped portion being screw-threaded and of such size as to screw 15 over the end of the tube 8, should it be desired to use it in that position. When in the latter position on the end of the tube 8, the perforations 27, together with the central opening, will form a spray consisting of a 20 series of small streams which will distribute the water over a considerable surface, and with great force.

In the normal operation of my improved nozzle, the tip of the ring 14 is turned so that 25 the conical part 9 contacts with the end of section 3 of the casing 2, thereby preventing any spray action. When it is desired to use this protective or distributing spray, the ring 14 is given a sufficient number of turns 30 to produce the desired volume of spray, which issues in the form of an even, practically unbroken hollow cone of water. Should the interior of a room or other compartment be filled with flame or smoke, so as to prevent 35 the entry of firemen, the entire nozzle may be inserted in a hole in the wall of such apartment, and the ring 15 screwed to such a position, that the backwardly directed openings, 16 are uncovered. The jets issuing 40 from these openings, together with the conical spray from the outer end of the tip, constitute a very effective and efficient distributor which will throw the water over the entire surface of the room or apartment in 45 which the nozzle is inserted. The use and application of the small attachments for the end of the tube 8 will be obvious to those familiar with the use of such devices in extinguishing fires.

Having thus described one form of my invention, I do not wish to be understood as being limited to the exact details of form and parts herein set forth, for various changes 55 may be made by those skilled in the art without departing from the spirit and scope of my invention.

What I claim and desire to protect by Letters Patent is:

1. A nozzle, comprising a casing, a screw-threaded tube located interiorly thereof, a screw-threaded part carried by said tube and coöperating with the end of said casing to form a spray opening, and arms connected with said screw-threaded part and extending 60 rearwardly over the exterior of said casing,

whereby said screw-threaded part may be adjusted and its removal permitted.

2. A fire-extinguishing nozzle, comprising a casing, a tube located interiorly thereof, an adjustable part connected with said tube by screw-threads and coöperating with the end of said casing to form a spray opening, arms connected with said adjustable part and extending to the exterior of said casing, and a ring rotatably carried by said casing and engaging said arms. 70

3. A fire-extinguishing nozzle, comprising a casing, a tube located interiorly of said casing, a screw-threaded part carried by said tube and coöperating with the outer end of said casing to form a spray nozzle, a ring carried exteriorly on said casing and connected with said screw-threaded part, the rear part of said casing having rearwardly directed openings, and a second ring adjustably carried by said casing adjacent the first-named ring and adapted to cover said rearwardly directed openings. 80

4. A fire-extinguishing nozzle, comprising a casing consisting of two screw-threaded parts, a union for joining said parts, a spider located interiorly of said union and held in position by parts of said casing, a screw-threaded tube carried by said spider, a conical part adjustably carried by said screw-threaded tube, a rotatable ring carried exteriorly of said casing, means connecting said conical part with said ring through which the former may be turned, said casing having rearwardly directed openings in its lower or inner end, and an adjustable ring carried by said casing and adapted to close said openings. 90

5. A fire-extinguishing nozzle, comprising an exteriorly threaded tube, reducing tips adapted to engage said tube, in combination with a spray tip having a central opening and a central screw-threaded projection, said tube being provided with a series of perforations adapted to form a series of circumferential jets, and an interiorly threaded flange on said tip whereby the said tip is adapted to be carried directly by said tube. 105

6. A fire-extinguishing nozzle, comprising an exteriorly threaded tube, reducing tips adapted to engage said tube, in combination with a spray tip comprising a disk having a central opening and a central hollow screw-threaded projection communicating with said opening, said disk being also provided with a series of perforations adapted to form a circular series of jets, and an interiorly threaded flange on said disk whereby said tip is adapted to be carried directly by said tube. 110

Signed this 31st day of December, 1908.
HENRY B. HELM.
